DESIGN FOR A FINGER SUPPORT FOR MANICURING OPERATIONS

John S. Jones, St. Louis, Mo.

Application November 17, 1944, Serial No. 116,403

Term of patent 14 years

(Cl. D86—10)

To all whom it may concern:

Be it known that I, John S. Jones, a citizen of the United States, residing in the city of St. Louis and State of Missouri, have invented a new, original, and ornamental Design for a Finger Support for Manicuring Operations, of which the following is a specification, reference being had to the accompanying drawing, forming part thereof.

Fig. 1 is a top plan view of a finger support

for manicuring operations, showing my new design;

Fig. 2 is a side view, and

Fig. 3 is an end view thereof.

I claim:

The ornamental design for a finger support for manicuring operations, substantially as shown.

JOHN S. JONES.
